UNITED STATES PATENT OFFICE.

BYRON PHELPS, OF SEATTLE, WASHINGTON.

DEFLECTOR FOR AIR-CURRENTS.

1,280,291.

Specification of Letters Patent. Patented Oct. 1, 1918.

Application filed November 5, 1917. Serial No. 200,283.

To all whom it may concern:

Be it known that I, BYRON PHELPS, a citizen of the United States, and resident of the city of Seattle, county of King, and State 5 of Washington, have invented certain new and useful Improvements in Deflectors for Air-Currents, of which the following is a specification.

My invention consists of a novel type of 10 deflector intended for use in places in connection with openings in a floor through which air is discharged, as radiator openings of hot air heating systems and its purpose is to provide a movable device which may be 15 placed over the opening so as to deflect the column of heated air to one side or the other, and also to provide a device of this character which may be folded so as to occupy slight 20 space, whereby it may be stored away when its use is not desired.

In the accompanying drawings I have shown my invention embodied in a type of construction which is now most preferred by me.

25 Figure 1 is a face view of the device when in folded position.

Fig. 2 is a section upon the line 2—2 of Fig. 1.

Fig. 3 is an end view of the device shown 30 in place over a radiator opening.

Fig. 4 is a side view of the device taken in section.

My device consists of three principal parts, a central section 1, and two side sections, 2, the latter being of triangular outline and pivotally connected by one edge respectively with opposite edges of the main or central section 1. The main or central section 1 is approximately of rectangular 35 shape. As herein shown, it is not strictly rectangular, one end being narrower than the other. It is, however, a four-sided plate-like body. This, as well as the triangular sides, are preferably made of a sheet of thin 40 material, such for instance as paste board, although metal might be used if this were desired.

In making this of paste board or material 45 of this character, I prefer to provide it with binding strips. The central section 1 is provided with a binding strip 10 at each of two opposite ends and I have also shown a third binding strip 10 located a short distance from one of the same ends. The two triangular 50 sides 2 are provided with binding strips 20 located along the two edges which are not adja-

cent to the central section 1. The latter edges of these triangular sides, as well as the sides of section 1, with which they are connected, do not need binding strips as these sides are 60 connected together by a hinge preferably composed of a strip 21 of cloth or suitable fabric which is glued or otherwise secured to the two sections. This permits the side sections 2 to fold down upon one side of the 65 central section 1, as is shown in Figs. 1 and 2.

The central section 1 is also preferably provided with a central reinforcing bar 11. This reinforcing bar, as well as the binding strips 20 of the side sections, may preferably 70 be made of wood. A brace 4, by which the side sections may be held in open position, is provided, this being preferably in the form of a wire bent in the general form of a flat V. The apex of this V is pivotally 75 mounted beneath a clip 40 which is secured to the reinforcing bar 11. The outer ends of the brace are bent upon ends 41 which are adapted to be slipped beneath and be secured by clips 42 which consist of a thin 80 metal strip secured by one end and having the other end slightly raised so that the end 41 of the brace rod may slide under and be securely held by the spring action of the clip 42.

To secure the sides in folded position I 85 pivotally mount an L-shaped bar or bolt 5 upon the reinforcing strip 11 at such point that it is close in the apex of the angle 90 formed between the two edges of the side sections 2, when the latter are folded down, as is clearly shown in Fig. 1. This being mounted to turn, it may be turned into such position as to overlap one of these sides and thus hold both sides down, or be turned into 95 such position that it will permit raising of the sides.

The device is shown in open position in 100 Figs. 3 and 4, in both cases being shown over a register 6. The triangular side sections 2 are preferably made with the two right angled sides of unequal length. The proportions of these sides may be made anything 105 desired. The device may thus be set so as to deflect the rising current of hot air squarely to one side or slightly to one side, as may be desired. For convenience in handling the device, especially when it is in open position, I provide a handle 7 which is secured to the reinforcing strip.

110 This device is very light in weight, may be folded into small space when not desired and

is readily opened out and held in open position when its use is desired. It is also cheap to manufacture and the construction is such that it would last a long time if given any kind of reasonable treatment.

What I claim as my invention is:

1. A deflector for hot air registers comprising two triangular sides and a third side hingedly connected by opposite sides with an edge of each of the triangular sides and brace members hinged upon the connecting side and having disengageable connection with the triangular sides.
- 10 2. A deflector for hot air registers having three sides hingedly joined to outline a wedge shaped body, a flat V-shaped brace rod pivoted at the apex of the V to the central of said sides and means for engaging the ends of said brace with the other sides to hold the sides open.
- 15 3. A deflector for hot air registers comprising a four sided plate-like member and two triangular side members each hinged by

one edge respectively to opposite edges of the first member, the central member having a reinforcing bar extending centrally thereof in like direction with its hinged edges, a V-shaped brace rod hinged at the apex of the V to said reinforcing bar and means for engaging its ends with the side plates to hold them open.

4. A deflector for hot air registers having a central plate provided with a reinforcing bar extending along its central line, two triangular plates hinged by an edge with respectively opposite ones of the edges of the central plate which are at the sides of the reinforcing bar, and adapted to fold down and overlap their corners, and a catch mounted upon the reinforcing bar and adapted to engage the said sides to hold them folded, and means for supporting said sides from the central plate to hold them in opened position.

Signed at Seattle, Washington, this 30th day of October 1917.

BYRON PHELPS.
